CLAIM

The ornamental design for a medicine cabinet having a reflective front face and sidewall, as shown and described.

DESCRIPTION

FIG. 1 is a top, front, and left side perspective view of a medicine cabinet having a reflective front face and sidewall showing my new design, the right side and rear being plain and unornamented;

FIG. 2 is a top plan view thereof, the bottom being a mirror image of that shown; and

FIG. 3 is a front elevational view thereof.

FIG. 1.

FIG. 2.

FIG. 3.
